UNITED STATES PATENT OFFICE.

JAHAN G. CARLSON, OF ROCKFORD, ILLINOIS. ASSIGNOR TO BURSON KNITTING COMPANY, OF ROCKFORD, ILLINOIS, A CORPORATION OF ILLINOIS.

TENSION DEVICE.

1,407,731.

Specification of Letters Patent. Patented Feb. 28, 1922.

Application filed April 23, 1920. Serial No. 376,070.

To all whom it may concern:

Be it known that I, JAHAN G. CARLSON, a subject of Sweden, residing at Rockford, in the county of Winnebago and State of Illinois, have invented certain new and useful Improvements in Tension Devices, of which the following is a specification.

This invention pertaining in general to knitting machines of the straight-row type, has more particular reference to a tension device therefor designed to impose a tension or drag on the yarn drawn to the yarn carrier.

In knitting machines of the straight-row type, the yarn-carrier by reason of its reciprocating action draws the yarn unevenly, in fact, to such an extent as to require a special form of elastic take-up for absorbing the jerky and unequal drawing action, and also to require tension devices designed to impose an even tension or drag on the yarn to prevent kinking and knotting thereof and to prevent it from being caught and broken on adjacent projections or parts, due to the uneven feed. It is the object of the present invention to provide a novel means for imposing the desired tension or drag on the yarn, which means shall serve also as an efficient guide for preventing the yarn from throwing and catching on adjacent parts under the impulses of the uneven feed.

Another object is to provide a tension device of the character in mind which shall cause a substantially uniform tension or drag and which shall also permit passage of a knot or any other obstruction on the yarn.

Referring to the drawing,—

Figure 1 is a side elevation of a yarn guiding structure as employed on a straight-row knitting machine, including a yarn tension device, embodying my improvements;

Fig. 2, an end view of the yarn tension device detached from the machine; and

Fig. 3, a side view of said device.

It will be noted that my improved yarn tension or drag may be employed at any of various positions on a knitting machine and that it is in no way limited to the particular application herein illustrated. The present example is in connection with a knitting machine of the straight-row type and by my improved tension device is applied to the frame of the machine just above the spool or bobbin support so that the yarn passes directly through this tension device and thence

through the overhead guides, a feed stop, a take-up arm and finally to the yarn-carrier. In the drawing, I have shown the yarn controlled in its passage to the yarn-carrier by a structure such as illustrated in Patent 1,072,365, September 2, 1913, and reference may be had thereto for a more thorough description of the yarn-guiding means. It will suffice to say that the yarn as shown in Fig. 1, is drawn at the end 4, from the spool or bobbin, then passes through my improved tension device, then through a tension 5, and through an eye 6 to a feed stop device 7, and then through the eye of a spring wire take-up arm 8 to the yarn carrier which reciprocates across the needle bed. The overhead yarn control devices have no bearing upon the present invention, and in this particular case the tension 5 is not essential.

Referring now to Figs. 2 and 3, it will be observed that my improvement consists, primarily, of a two-part tension device, designated generally by a base member 9 and a movable tension or drag member 11. The base member 9 may be rigidly supported in any suitable manner, and has an opening 12 up through which the yarn is drawn. The drag member 11 is simply a flat piece of metal resting on a flat upper surface of the base member 9 and is held in position by a pair of upright posts or guides 13 adjustably mounted on the base member 9. The drag member 11 is free to rise and fall, and the apertures 14 through which the guide members 13 pass are of sufficient size to allow plenty of play so that the drag member may be tilted on its longitudinal edge 15 as indicated in dotted lines in Fig. 3 by the drawing action of the yarn. The guide posts 13 are turned laterally at their upper ends to prevent displacement of the drag member and by reason of this construction said drag member may be withdrawn lengthwise of the posts. Said member may be similarly slid back onto the posts; consequently more than one of such members may be slipped onto said guide posts to increase the tension, according to the conditions at hand. The extent of this tension or drag may also be varied by adjusting the position of the drag member with relation to the opening 12, and to this end I have provided suitable means, such as a screw connection 16 for adjusting the guide posts 13 toward and from the opening 12.

From the foregoing, it will be manifest that as the yarn is drawn through this tension device any jerk or unsteady action will be absorbed by tilting or lifting the member 5 11; and in the event that the yarn carries a knot or any ordinary enlargement the latter will pass freely under the member 11, aided by the clearance provided for this purpose in the form of a suitable depression or 10 bevel 17 over which the yarn is drawn.

While I have illustrated but a single working embodiment of my improvements, it should be understood that various changes might be made in the construction without 15 departing from the spirit and scope of the invention as expressed in the appended claims, in which—

I claim:

1. A yarn tension device comprising a flat 20 base member having a yarn opening, a tension member in the form of a flat plate resting on said base member with one edge adjacent to said opening, means holding said tension member in operative relation to said 25 opening, whereby the yarn passing through said opening will extend beneath and across said edge and to the opposite edge of said member and thence upwardly, and said means permitting the tension member to be 30 raised on its first mentioned edge under the influence of the yarn on the opposite edge.
2. A yarn tension device comprising a flat 35 base member having a yarn opening, a tension member in the form of a flat plate resting on said base member with one edge adjacent to said opening means holding said tension member in operative relation to said opening, whereby the yarn passing through 40 said opening will extend beneath and across said edge and to the opposite edge of said

member and thence upwardly, said means permitting the tension member to be raised on its first mentioned edge under the influence of the yarn on the opposite edge, and means for adjusting said tension member toward and from said opening, whereby to 45 vary the proximity of said first mentioned edge to said opening.

3. A yarn tension device comprising a base 50 having an opening, a pair of upright posts supported on said base member and having laterally turned upper ends, a tension plate shaped to slip lengthwise over said posts and to rest on the base member with one edge adjacent to said opening and having a 55 limited tilting movement on said edge as a fulcrum, the yarn passing through said opening, laterally beneath the tension member and being drawn upwardly at the edge of said member farthest from said opening.

4. A yarn tension device comprising an inclined base member having an opening, a tension member resting on said inclined base member above said yarn opening, and means holding said tension member in operative position on the base and with capacity to tilt upwardly upon its edge disposed adjacent to said opening, the yarn passing upwardly through said opening, laterally beneath the tension member, and thence being 65 drawn upwardly at the high end of said member.

5. A tension device comprising a base, a tension plate resting on the base and having opposed edges beneath which the yarn is 70 successively drawn, the first edge constituting a fulcrum upon which the plate may be tilted by the action of drawing the yarn upwardly over the second edge.

JAHAN G. CARLSON.
